Fig. 1.

Fig. 2.

FIG. 1 is a top perspective view of a packaging tray for eggs or other fragile articles showing our new design;

FIG. 2 is a top plan view thereof;

FIG. 3 is a front elevational view thereof;

FIG. 4 is a side elevational view as seen from the right of FIG. 2; and

FIG. 5 is a bottom plan view thereof.

The characteristic features of the design reside in a packaging tray for eggs or other fragile articles having a plurality of upwardly projecting hollow half posts arranged along two opposite sides of the tray and with the outwardly facing surface of each half post being convex; a plurality of upwardly projecting hollow full posts disposed intermediate downwardly extending pockets and with the surfaces of the full posts being concave and extensions of the pocket surfaces and conforming to the concavity of the latter surfaces; the top surfaces of the full posts being substantially diamond-shaped; and an upwardly extending, hollow, curved protuberance formed at each corner of the tray, the height of each protuberance being less than the heights of the full and half posts and portions of each protuberance extending along the sides of the tray defining the corner.

We claim:

The ornamental design for a packaging tray for eggs or other fragile articles, substantially as shown and described.
